UNITED STATES PATENT OFFICE.

CHARLES H. HODGKINS, OF PITTSBURGH, PENNSYLVANIA, ASSIGNOR TO WESTINGHOUSE ELECTRIC & MANUFACTURING COMPANY, A CORPORATION OF PENNSYLVANIA.

CIRCUIT INTERRUPTER.

Application filed July 15, 1920. Serial No. 396,330.

My invention relates to circuit interrupters and particularly to circuit interrupters of the quick-acting type.

One object of my invention is to provide a circuit interrupter that shall be adapted to open and close quickly upon a relatively small movement of the operating handle.

Another object of my invention is to provide a toggle device for a circuit interrupter and a double-acting spring that shall be adapted to quickly reset the toggle device and close the contact members and to so tension another spring during the closing operation that, when the contact members are released, the other spring will quickly disengage the same.

A further object of my invention is to provide an interrupter of the above indicated character that shall be relatively inexpensive to construct and effective in its operation.

In my Patent No. 1,424,304, issued Aug. 1, 1922, there is disclosed a somewhat similar circuit interrupter embodying a contact carrying shaft, an operating shaft, a sleeve 25 on the operating shaft, a toggle mechanism at one end of the sleeve connecting the same to the operating shaft and a bell-crank mechanism at the other end of the sleeve connecting the same to the contact-carrying shaft.

In practicing my invention, I propose to accomplish the same operating results as with the above mentioned device and to further economize and render the device more compact and effective by the rearrangement of parts and the elimination of the above mentioned bell-crank mechanism and one of the shafts.

I provide an operating shaft, a contact-carrying sleeve disposed around the operating shaft and relatively movable with respect thereto and a toggle mechanism connected to the sleeve and, through a pin-and-slot, lost-motion connection, to the operating shaft. A double-acting spring is connected through a pin-and-slot, lost-motion connection to the toggle mechanism and is adapted to be moved to one side of its dead-center position when the toggle mechanism is set and to the other side thereof to quickly close the interrupter. The closing of the inter-

rupter is adapted to so tension another spring that, when the toggle mechanism is upset, the other spring quickly opens the interrupter.

Figure 1 of the accompanying drawings is a fragmentary perspective view of a circuit interrupter embodying my invention, with the various parts in relative position but spaced apart for clearness, the interrupter being in its open position, and Fig. 2 is a plan view of a portion of the tripping mechanism.

A circuit interrupter 1 comprises, in general, a casing 2, an oil-containing receptacle 3, stationary contact members 4, movable contact members 5, an operating handle 6 and an operating mechanism 7.

The stationary contact members 4 are mounted on an insulating rod or bar 8 that is secured to the walls 9 and 10 of the receptacle 2. The handle 6 is mounted on a rod or shaft 15 that is rotatably supported at one end in the wall and extends loosely into one end of, and for some distance along, an insulated sleeve structure 11 having a bearing pin portion 15a mounted in the wall 10. The sleeve 11 supports the movable contact members 5, on a line parallel to the rod 8.

Levers 21 and 22 are secured to the respective ends of the sleeve 11, the lever 22 having an arm 23 for a purpose to be hereinafter described, and an arm 24, the outer end of which is connected to a rod 12 through a tension spring 25. The rod 12, having an insulating sleeve 13 thereon, is mounted in the walls 9 and 10 of the receptacle 2 and is adapted to support terminal members 14 for the movable contact members 5. An arm 16 having a relatively short pin 17 therein and an arm 18 having a projection 19 thereon are mounted in closely adjacent planes on the shaft 15 near the handle 6.

The pin 17 extends through an opening 17a in the arm 18 into an arcuate slot or opening 30 in an arm 28 of a member 27 having two arms 28 and 29 and loosely mounted on the shaft 15. The arm 29 is provided with an opening or slot 31 that is adapted to receive a pin 32 which is mount-

wardly-bent portions 62 mounted on the pin 60, by which the lever 61 is pivoted, is biased in the counter-clockwise direction, as viewed from the left, by a compression spring 63 that extends between an upper horizontal offset portion 64 of the plate 47 and a relatively short arm portion 65 of the lever 61.

The lever arm 61 also has transversely extending arms 66 and 67 extending to positions over vertically disposed striking rods 68 that are actuated by overload coils 68a supported at the rear of the plate 47. The arm 66 has a portion 69 extending beyond the position at which it is engaged by its co-operating striking rod 68 to a position at the opposite side of the pin 60 where it has a downwardly extending portion 70 for engagement with the latch member 38.

Upon the occurrence of an overload, the rods 68 will be actuated upwardly to move the lever arm 61 clockwise, as viewed from the left, about the pin 60. The portion 70, being on the opposite side of the pin 60 to that occupied by the rods 68, will thus be depressed to engage the latch member 38. This will cause the toggle mechanism to buckle and the interrupter to be opened.

The interrupter will not remain closed during the existence of a predetermined overload as, under this condition, the portion 70 will immediately be moved to actuate the latching member 38 to buckle the toggle mechanism, nor may the interrupter be closed at times of predetermined low or no voltage on the line. Under the latter conditions, the portion 53 will be held, by the spring 55, in position to intercept the latching member 38 to prevent the setting of the toggle mechanism.

While I have shown and described a particular form of my invention, changes may be effected therein without departing from the spirit and scope thereof, as set forth in the appended claims.

I claim as my invention:

1. In a circuit interrupter, the combination with movable and stationary contact members and an operating shaft, of a cylindrical member for carrying the movable contact member loosely mounted on the operating shaft, a lever arm loosely mounted on the operating shaft and having a lost-motion connection therewith by means of which it may be caused to rotate with the shaft a toggle mechanism connected between the lever arm and the cylindrical member, and a double-acting spring connected through a pin-and-slot connection to the lever arm.

2. In a circuit interrupter, the combination with movable and stationary contact members and an operating shaft, of a member loosely mounted on the operating shaft, said movable contact member being mounted on said loosely mounted member, a lever arm loosely mounted on the shaft but hav-

ing a lost-motion connection therewith, two links operatively connected between said lever arm and the movable member to constitute a toggle mechanism, a latch mounted on one of the links for maintaining the toggle mechanism in its set position, a double-acting spring cooperating with said lever arm to move it in one direction over its dead-center position when the toggle mechanism is being set and in the other direction to close the contact members, and a single-acting spring connected to, and to be tensioned by, the movable member during the closing operation of the interrupter.

3. In a circuit interrupter, the combination with a movable contact member and an operating handle mounted for movement about a common axis, a turnable member operatively connected to the movable contact member, a toggle mechanism disposed between the operating handle and the turnable member, and a double-acting spring operatively connected to said handle and said toggle mechanism, to be moved to one side of its dead-center position when the toggle is set and to the other side when the handle is moved to the closing position.

4. In a circuit interrupter, the combination with co-operating movable and stationary contact members, and an operating handle, of a toggle mechanism, a double-acting spring co-operating with said toggle mechanism, to be moved to one position when the toggle mechanism is set and for quickly closing the contact members when moved to its other position, and a single-acting spring co-operating with said toggle mechanism, to open the contact members when the toggle is upset, the operating handle and the movable contact member being mounted for rotative movement about a common axis.

5. In a circuit interrupter, the combination with co-operating movable and stationary contact members, and an operating handle, of a toggle mechanism, a double-acting spring, co-operating with said toggle mechanism, to be moved to one position when the toggle mechanism is set and for quickly closing the contact members when moved to its other position, and a single-acting spring, co-operating with said double-acting spring and said toggle mechanism, to be tensioned when the contact members are closed for the purpose of quickly opening the same when the toggle mechanism is upset, the operating handle and the movable contact member being mounted for rotative movement about a common axis.

6. In a circuit interrupter, the combination with co-operating movable and stationary contact members and an operating handle, of a toggle mechanism connected between the handle and the movable contact member, and a double-acting spring, co-operating with said toggle mechanism, to be

moved to one position when the toggle is set by movement of the handle in one direction and to be moved to its other position to quickly close the contact members when the handle is moved in the other direction, the operating handle and the movable contact member being mounted for rotative movement about a common axis.

7. The combination with movable and stationary contact members and an operating handle, of a toggle mechanism disposed between the handle and the movable contact member, a spring, co-operating with said toggle mechanism, to be moved to one

side of its dead-center position by the handle 15 when the toggle mechanism is set and to other side of its dead-center position when the handle is moved to its closed position, and a second spring, co-operating with said first spring, to be tensioned when the contact members are closed, the operating handle and the movable contact member being mounted for rotative movement about a common axis.

In testimony whereof, I have hereunto 25 subscribed my name this 26th day of June, 1920.

CHARLES H. HODGKINS.
